ATTORNEY.

UNITED STATES PATENT OFFICE.

AUBREY J. BECK, OF ERIE, PENNSYLVANIA.

RAIL JOINT.

Application filed October 27, 1920. Serial No. 420,039.

To all whom it may concern:

Be it known that I, AUBREY J. BECK, a citizen of the United States, residing at Erie, in the county of Erie and State of Pennsylvania, have invented certain new and useful Improvements in Rail Joints, of which the following is a specification.

This invention relates to improvements in rail connection and has for its object 10 to provide a combined rail joint and seat.

Another object of the invention is to provide a boltless rail joint.

Another object of the invention is to provide a combined rail joint and seat formed 15 in longitudinal spaced apart sections.

With the above and such other objects in view as may hereinafter appear, I have invented the device illustrated in the accompanying drawings in which—

20 Figure 1 is a side elevation of a section of railway embracing my invention.

Figure 2 is a top plan view thereof.

Figure 3 is a bottom plan view thereof.

25 Figure 4 is a section on line 4—4 Figure 1.

Figure 5 is a similar view looking in the opposite direction.

Figure 6 is a section on line 6—6 Figure 1, illustrating the locking means.

30 Figure 7 is a detail perspective view of one section of the device.

Figure 8 is a fragmental detail showing one end of Figure 1 with a bridge member removed.

35 Figure 9 is a detail of a bridge member.

Like reference characters indicate like parts throughout the following specification and in the several views in the drawings in which 1 indicates a section of railway 40 showing a rail joint embracing my invention, and 2 and 3 are abutting rail ends.

These ends are held together by the rail seat 4 formed of a pair of similar members 5 and 6 having a base part 7 and 8 with 45 inwardly projecting flanges 9 and 10 upon which the sides 11 and 12 of the rail bases 13 and 14 seat. Projecting upwardly from said parts 7 and 8 and seating on top of the opposite sides of the rail base flanges 50 or sides 11 and 12, are channel forming members 15 and 16 between which the webs 18 and 18' of said rail ends 2 and 3 are held.

The seat members 5 and 6 are held fixedly 55 secured to the rails 2 and 3 by means of a centrally disposed bridge member 19 and

end bridge members 20 and 21, the parts 15 and 16 extending at both ends beyond their bases, the extensions 22 and 23 at one end and 24 and 25 at the other end in conjunction with the rail flange forming three 60 triangularly disposed sides upon which the members 20 and 21 similarly formed, seat, thus binding the ends of the members 15 and 16 securely to the rails. The bridge 65 19 is made of a size and shape to fit over the seat forming members 5 and 6 and is provided with an upwardly projecting middle portion 26 which seats up between the base portions 7 and 8 forming a guide for 70 the bridge in placing it and also forming a spacer for the members 5 and 6. A wedge shaped passage 27 extends longitudinally through the bridge 19 adjacent its under side 28, said passage aligning with grooves 75 29 and 30 in the bottom of the members 7 and 8 whereby a wedge or locking key 31 when driven through the passage 27 forms means for locking the bridge 19 and in its proper operative position which is in alignment with the abutting ends of rails 2 and 3 whereby said ends are doubly secured 80 against being moved out of perfect alignment with one another. Several openings 32 are provided in the reduced end 33 of 85 wedge 31 for receiving the open ring 34 or other means for preventing accidental displacement of said wedge.

In adjusting the device to the rails the bridge rings 19, 20 and 21 are first slipped 90 over the flanges of the rail ends and out of the way of the seat members until they have been seated in place, after which the bridge 19 is slipped into place and then the bridges 20 and 21 are brought into their 95 proper position.

The inner end 35 of the bridge member 19 is formed on a lower plane than its outer end 36 in order to permit the flanges of car wheels to pass over without touching the 100 bridge.

The inner surfaces of the members 15 and 16 are provided with lugs 17, seating in slots 17' formed in the rail webs 18 and 18', whereby the rails and rail engaging 105 members are held in proper relative position.

Having now described my invention, that which I claim to be new and desire to procure by Letters Patent is:—

110 1. A rail joint consisting of a pair of rail engaging members provided with project-

ing inclined ends and bridge clamps for binding said members to rail ends, said bridges being triangular in shape and a centrally disposed clamp having openings and 5 a key projecting through said openings to link said members together.

2. A rail joint consisting of a pair of rail engaging members provided with projecting inclined ends and bridge clamps for binding 10 said members to rail ends, said bridges being triangular in shape and a centrally disposed clamp having openings and a key projecting through said openings to link said members together, said members having 15 recesses in which the key seats.

3. A rail joint consisting of a pair of rail engaging members provided with projecting inclined ends and bridge clamps for binding 20 said members to rail ends, said bridges being triangular in shape and a centrally disposed clamp having openings and a key projecting through said openings to link said members together, said members having recesses in which the key seats, said 25 members having lugs to seat in recesses formed in said rails.

4. A pair of members forming a rail seat, each member having a longitudinal channel for receiving the flange of the rail, a clamp 30 for binding said members together, said clamp bridging said flange, and having a boss projecting between said members, means for locking said clamp in place, said means 35 consisting of a key projecting through a passage in said clamp and seating in recesses in said members.

5. A pair of members forming a rail seat, each member having a longitudinal channel for receiving the flange of the rail, a clamp 40 for binding said members together, said clamp bridging said flange, and having a boss projecting between said members, means for locking said clamp in place, said means 45 consisting of a key projecting through a passage in said clamp and seating in recesses in said members, said seat members having rail web engaging flanges.

6. A pair of members forming a rail seat, each member having a longitudinal channel 50 for receiving the flange of the rail, a clamp for binding said members together, said clamp bridging said flange, and having a boss projecting between said members, means for locking said clamp in place, said 55 means consisting of a key projecting through

a passage in said clamp and seating in recesses in said members, said seat members having rail web engaging flanges, said flanges projecting beyond the bases of said seat members.

7. A pair of members forming a rail seat, each member having a longitudinal channel for receiving the flange of the rail, a clamp for binding said members together, said clamp bridging said flange, and having a 60 boss projecting between said members, means for locking said clamp in place, said means consisting of a key projecting through a passage in said clamp and seating in recesses in said members, said seat members 65 having rail web engaging flanges, said flanges projecting beyond the bases of said seat members, means for binding said projections to said rail.

8. A pair of members forming a rail seat, 70 each member having a longitudinal channel for receiving the flange of the rail, a clamp for binding said members together, said clamp bridging said flange, and having a boss projecting between said members, means 75 for locking said clamp in place, said means consisting of a key projecting through a passage in said clamp and seating in recesses in said members, said seat members having rail web engaging flanges, said flanges projecting beyond the bases of said seat members, means for binding said projections to 80 said rail, said means consisting of bridges.

9. A pair of members forming a rail seat, 85 each member having a longitudinal channel for receiving the flange of the rail, a clamp for binding said members together, said clamp bridging said flange, and having a boss projecting between said members, means for locking said clamp in place, said means 90 consisting of a key projecting through a passage in said clamp and seating in recesses in said members, said seat members having rail web engaging flanges, said flanges projecting beyond the bases of said seat members, means for binding said projections to 95 said rail, said means consisting of bridges, shaped to conform to the shape of said projections and the bottom of said rail.

In testimony whereof I affix my signature 100 in the presence of two witnesses.

AUBREY J. BECK.
